(57) **CLAIM**

The ornamental design for a flash drive, as shown and described.

DESCRIPTION

FIG. 1 is a front perspective view of a flash drive showing my design.

FIG. 2 is a rear perspective view of the flash drive in FIG. 1.

FIG. 3 is a front elevation view of the flash drive in FIG. 1. FIG. 4 is a rear elevation view of the flash drive in FIG. 1. FIG. 5 is a left side elevation view of the flash drive in FIG. 1.

FIG. 6 is a right side elevation view of the flash drive in FIG. 1.

FIG. 7 is a top plan view of the flash drive in FIG. 1.

FIG. 8 is a bottom plan view of the flash drive in FIG. 1.

FIG. 9 is a front perspective view of the flash drive in FIG. 1, shown in an alternate configuration; and,

FIG. 10 is a rear perspective view thereof.

The broken lines in the drawings show portions of the flash drive that form no part of the claimed design.

1 Claim, 10 Drawing Sheets
